UNITED STATES PATENT OFFICE.

FERDINAND BURCHARTZ, OF NEW YORK, N. Y., ASSIGNOR TO BURCHARTZ FIRE-PROOFING COMPANY, INC., OF NEW YORK, N. Y., A CORPORATION OF NEW YORK.

REINFORCED-CONCRETE FLOOR AND CEILING CONSTRUCTION.

1,140,571.

Specification of Letters Patent.

Patented May 25, 1915.

Application filed January 10, 1912. Serial No. 670,352.

To all whom it may concern:

Be it known that I, FERDINAND BURCHARTZ, a citizen of the United States, and resident of the borough of Manhattan, city, county, and State of New York, have invented certain new and useful Improvements in Reinforced-Concrete Floor and Ceiling Constructions, of which the following is a specification.

- 10 My invention relates to reinforced concrete floor and ceiling constructions of the kind in which open-ended blocks or tiles are arranged with their longitudinal axes extending at an angle to each other so as to 15 form intersecting channels for tie-rods and cement or other coalescent material and in which the open ends of each block or tile are closed by portions of adjacent blocks or tiles.
- 20 My improvement has for its object to provide an improved block or tile which is extremely light in weight, simple in construction and consequently cheap to manufacture and which is preferably made of individual 25 parts which occupy a minimum of space and may consequently be readily shipped in large quantities and securely packed to 30 guard against breakage during handling or shipment and which may further be readily and quickly set up in operative position by substantially unskilled labor.

My invention will be fully described hereinafter and the features of novelty will be pointed out in the appended claims.

35 Reference is to be had to the accompanying drawings in which—

Figure 1 is a cross-sectional view of one form of my improved block or tile; Fig. 2 is a similar view of another form thereof; 40 Fig. 3 is a sectional elevation of a portion of a floor or ceiling with the form of block shown in Fig. 1 incorporated therein; Fig. 4 is a similar view showing use of the block 45 illustrated in Fig. 2 and Fig. 5 is a plan view of Fig. 3.

Referring more particularly to the form of my invention shown in Fig. 1 of the drawings the tile or block comprises two elements A and B each of which is substantially U-shaped in cross-section. The element A is composed of a main portion α and members α' which latter extend from opposite edges of said portion α at preferably right angles thereto and are prefer-

ably integral therewith. The element B is 55 similarly formed with a main portion b from the opposite edges of which members b' project in such a manner as to be preferably perpendicular to said main portion b . These members b' are likewise preferably 60 made integral with the said main portion b and are further provided at their free ends with flanges b^2 as clearly shown in Fig. 1. The elements A and B may be made of any 65 suitable material such as terra cotta, concrete or the like, metal, wire screening or mesh, wood or in fact any other material which can be formed or built into the desired shape or structure and which is suitable for the purpose intended. If the elements are made of material which can be 70 properly manipulated they may each be made in one single piece, while if made of wood or the like the members α — α' and b — b' — b^2 may be separate pieces properly 75 secured together by screws, nails or other fastening medium. In all cases the material of which the element A is made is 80 preferably lighter in weight than the material of which the element B is constructed thus reducing the weight of each assembled 85 block to a minimum without in any way affecting its efficiency. In other words the material of which the element A is formed need only be heavy enough so that the members α' will effectually resist or prevent the 90 entrance of any of the coalescent material to the interior of the block as this element A in the finished construction is not called upon to sustain any part of the weight of the completed floor or ceiling. On the other hand the element B must be made sufficiently rigid to resist the pressure of the 95 particular coalescent material which may be used in the floor or ceiling in which the blocks are incorporated.

In actual use the element B in an inverted position is placed within the element A intermediate of the members α' and preferably 100 centrally thereof with the flanges b^2 resting upon the inside surface of the main portion α after which, if desired, suitable fastening means C such as clips or the like may be passed through said portion α and said flanges b^2 to secure the two elements together in a unitary structure. These fastening means C are however not absolutely necessary and may be omitted and if used

at all are preferably introduced at or just prior to the time the blocks are to be actually incorporated in the floor or ceiling being constructed. After being thus assembled 5 the completed block in cross-section has substantially the form of double U's each U being inverted with respect to the adjacent U. In other words the members a' and b' together with that part of the portion a located therebetween form a U extending in one direction, while the members b' and b form a U extending in the opposite direction. In this assembled condition the blocks comprising the two elements A and B are 10 placed upon the usual temporary scaffolding or centering with the axes of adjacent blocks extending at substantially right angles to each other and in such a manner that the members a' of each element A will extend 15 across and close the one open end of two oppositely located adjacent blocks as clearly shown in Fig. 3. With this arrangement intersecting channels D are formed in which the usual tie rods E are placed and which 20 are adapted to receive cement or other coalescent material which material in some cases may also extend over and cover the outer surfaces of the elements B. It will be seen that in the finished structure, the free 25 ends of the members a' and the outer surfaces of the elements B are located in a common plane, and that said members a' are of a width sufficient to extend beyond the inner surfaces of the members b'. The said members a' will thus completely cover the open 30 ends of the blocks and prevent the entrance of the coalescent material to the interior of said blocks. It will further be seen that the channels D are periodically interrupted by 35 spaces D' formed between opposed or adjacent ends of the short channels of each block formed by the members a' and b' into which spaces the coalescent material is also introduced. This material located in said 40 spaces D' when set thus forms keys or projections which serve to maintain said blocks against any lateral movement relatively to each other so that a solid monolithic floor or ceiling results. The arrangement of blocks 45 is substantially the same as in my copending application Serial No. 607,759 filed February 10, 1911.

By making the elements A and B separate from each other, the elements of each species 50 may be readily nested, particularly when made of a material which is capable of being bent, so as to occupy a minimum of space and at the same time be solidly packed together to prevent injury during handling 55 and shipment. A large number of blocks may thus be included in a single shipment and are readily handled and assembled after having reached their destination. It is of course to be understood, should it at any 60 time and for any reason be desirable, that

the elements A and B may be assembled and connected to form complete blocks before being shipped.

In the form of my invention shown in Fig. 2 the block is formed of an element A' 70 which comprises a main portion a² from which members a³ extend at preferably right angles thereto. Members a⁴ project from the members a³ in a direction parallel to the portion a² while members a⁵ extend from the members a⁴ in a direction parallel with the members a³, the dimensions of the said members a⁵ being such that the free ends thereof and the main portion a² are located in a substantially common plane. In other 80 words the element A' is so formed as to have channels a⁶ and a⁷ which open or face in opposite directions as clearly shown in Fig. 2. Thus this form of block in cross-section also has substantially the form of 85 double U's with each U inverted with respect to the adjacent U. That is the members a³, a⁴ and a⁵ form one U extending in one direction, while the two members a³ and the member a² form a U extending in the 90 opposite direction. With this construction the members a³ and a⁵ form the side walls of the intersecting channels while the members a⁴ form the bottoms thereof. These elements A' are preferably used in connection 95 with an element B' which is preferably flat and of a size to accommodate a number of said elements A' and which is adapted to extend across and cover the channels a⁷. If the element B' is used clips or other fastening devices C' similar to the devices C serve to secure the two elements A' and B' together and to suspend said element B' from the elements A' after the centering has been removed. The element B' as well as the element A' may be made of the same materials as are the elements A and B, that is of any material suitable for the purpose intended. In using this form of my invention the element B' is first placed upon the 100 temporary scaffolding or centering after which the elements A' are placed thereon and secured thereto, in such a manner that the longitudinal axes of adjacent blocks extend at substantially right angles to each 105 other and so that the members a⁵ extend across and completely close the open ends of the two adjacent oppositely located elements A' in the same manner as shown in Fig. 5. In this form of my invention the element 110 B' if used extends across the spaces between the inside surfaces of the members a³ or in other words across the channels a⁷ and serves to close said spaces or channels and provides a ready and convenient support for plaster 115 or the like. If desired this element B' may be omitted in which case the elements A' would be placed directly on the temporary scaffolding or centering. Otherwise this 120 form of my invention is the same and has 125 130

the same advantages as the form shown in Fig. 1.

In both forms of my improvement the concrete or other coalescent material in the 5 intersecting channels in addition to binding the blocks into a solid monolithic structure forms concrete or other beams or girders reinforced by the tie-rods and acting as load carrying elements thus providing a structure 10 of a minimum dead weight yet capable of sustaining heavy loads.

It is to be understood that the members b' and a^3 need not be parallel with the members a' and a^5 respectively and that said 15 members b' and a^3 may be inclined with respect to said members a' and a^5 so that the channels formed by these members will be narrower at the bottom than at the top, thus securing a saving of material without affecting 20 the utility of the blocks. Furthermore, the member b and a^2 may be so disposed as to form conical or other upper surfaces to secure a more perfect arch construction.

Various changes in the specific forms 25 shown and described may be made within the scope of the claims without departing from the spirit of my invention.

I claim:

1. The combination of two channelled 30 units, one unit being located within the other and inverted with respect thereto, said

inner unit being of less width than the outer and forming therewith an open ended complete block provided with open channels extending lengthwise thereof at opposite sides. 35

2. The combination of two channelled units, one unit being located within the other and inverted with respect thereto, said inner unit being of less width than the outer and forming therewith an open ended complete 40 block provided with open channels extending lengthwise thereof at opposite sides, and means for securing said units together.

3. The combination of two channelled units, one unit being located within the other 45 and inverted with respect thereto, said inner unit being of less width than the outer and forming therewith an open ended complete block provided with open channels extending lengthwise thereof at opposite sides, 50 flanges extending along opposite sides of said inner unit and arranged to rest upon a portion of the outer unit and means for securing said flanges to said outer unit.

In testimony whereof, I have hereunto set 55 my hand in the presence of two subscribing witnesses.

FERDINAND BURCHARTZ.
